CLOTHES DRIER

Ransaeller J. Jenks, Lewiston, Idaho

Application February 1, 1937, Serial No. 123,455

1 Claim. (Cl. 211—86)

This invention relates to improvements in clothes drying rack structures primarily intended for household use.

One of the objects of this invention is to provide a rack structure of maximum capacity for pieces of all sizes, and a further object is to provide such a structure in a form and an assembly that will be foldable into a minimum of space and size.

10 In the most improved form, the structure includes a central rack supporting standard with clothes drying racks radiating therefrom, and it is a very special feature to provide a central standard that is normally unstable, and which 15 is provided with means for engaging opposed room areas such as the floor and ceiling to render said standard stable when in use. By means of this novel arrangement, I avoid the necessity of providing the standard with a supporting base 20 large enough to render the structure self stable when in the performance of its drying function.

A further object and feature is to provide interacting and interdependently connected and detachable rack and supporting bars connected 25 with each other and with said standard in a manner to be effectively supported in a functioning position and capable of being partly detached and folded into compact relation peripherally about the standard when in a non-functional adjustment.

An additional object is to provide a source of supply of heated air located upon the rack supporting standard in a position to be most effective upon the clothes suspended from the racks, 35 and a still further or alternative feature is to equip the standard with a means for causing circulation of the heated air, or unheated air.

A further object is to not only increase the drying capacity but also to render the drying 40 action more effective by the provision of means whereby large area pieces like sheets can be suspended about the radially outer ends of the drying racks in a circumferentially depending position with respect to the standard in such 45 a manner as effectively to concentrate and localize the application of heated air upon the clothes suspended on the racks inside of said large area pieces.

The invention has many other objects and 50 functions which will be more fully described in connection with the accompanying drawings and which will be more particularly pointed out in and by the appended claim.

In the drawings:—

55 Fig. 1 is a view in side elevation of my im-

proved drier showing rack portions at the left thereof adjusted into a functioning position and rack portions at the right partly folded up.

Fig. 2 is a plan view section on line 2—2 of Fig. 1.

Fig. 3 is a view in elevation showing the drier in a folded or non-functioning position.

Fig. 4 is a view in side elevation showing how sheets or other large area pieces may be hung in peripheral relation about the rack structure. 10

Fig. 5 is a sectional view on line 5—5 of Fig. 1.

Fig. 6 is a sectional view on line 6—6 of Fig. 5.

Fig. 7 is a detail view of one of the bars.

Like characters of reference designate similar parts throughout the different figures of the 15 drawings.

As shown, the drier includes a central standard which may be tubular and which is designated at 1. A relatively small but suitable base is shown at 2, and is conveniently connected in 20 rigid relation with said standard 1, and is provided with a friction pad 3 of felt or the like, for engagement with the floor 4. The standard 1, is extensible, and in the present construction, the part 1, is the lower section of said standard. 25 An upper section is indicated at 4, and the same telescopes section 1 and may be held in its adjusted position by means such as a set screw 5. The upper end of section 4 is enlarged or provided with a head 6, having a pad 7, of felt or 30 the like for engagement with the ceiling 8, or a beam or rafter which may be the equivalent of a ceiling.

With the racks extended, as will later be described, it will be clear that this standard would 35 be normally unstable and it is the function of this extensible feature, together with the devices 2 and 6, for engagement with the floor and ceiling, to render the structure effectively stable when in a functioning position of adjustment, 40 as will later appear.

Section 1 is provided with a plurality of rack bar heads, which, in the present construction are two in number, but it will be understood that any desired number may be employed in view of 45 the present disclosure. The upper head is indicated at 9 and the lower head at 10, and as they are identical in form and function only one need be described in detail.

Referring to Figs. 5 and 6, the head 10 is shown 50 as a flat circular body which may be of wood or any desired material. The head 10 is mounted on a flange 11, of a collar 12, that is adjustable on section 1, and provided with a set screw 13, to hold the head in an adjusted position length- 55

wise of section 1. The head 10 terminates at 14, at its inner perimeter and is provided with a series of radially disposed grooves 15 of a depth substantially equal to one dimension of the bars, 5 to be later described. These grooves extend from the inner portion 14 outwardly through the periphery and are equal in number to the number of rack entities employed. Intersecting each groove are transversely disposed notches 16, for 10 a purpose that will presently appear.

Above head 9, section 1 is provided with a collar 17, having a flange 18, and a set screw 19, whereby the collar may be fixed in adjusted positions. The flange 18 is provided with a series 15 of stringers 20, which may be cords or flexible wires, and on the outer end of each stringer is a clothes-pin or suitable clip 21, the purpose of which will later appear.

In many cases, an effective circulation of air 20 will greatly hasten the drying action and hence it is a feature of the invention to provide means on the standard for causing such circulation. One such means may be in the form of a fan having blades 22 and an electrically driven body 25 23, to which the blades 22 are attached. This body may be rotatively mounted on section 1, between thrust collars 24. A cable 25, may lead to a source of current, as will be clearly understood.

30 Where the drier is disposed in a cold or cool room, and also in many other instances, a source of heat to raise the temperature of the air is valuable. Hence, it is a feature of this invention to provide the standard 1 with an air heater, 35 which of course may be used supplementally with the fan, or alternately with respect thereto, it being clear that under some conditions both would be desirable while under other conditions only one would be of advantage.

40 Any desired form of air heater would be within the province of this invention but I have shown a shell 26, disposed about section 1, and near the base thereof, and this shell is provided with a series of openings 27. Within the shell 26, I may provide resistance wires 28, suitably 45 connected with a source of current through leads 29 and 30. It will be understood that leads 29 and 30, and also cord 25, may be plugged into outlets in the usual manner, the main feature being that my improved standard is equipped 50 with these circulation and heating features as an integral part of its structure. Thus, whenever or wherever the device is employed, these features will be available not only for service, but will be located in the most effective position 55 to render such service.

Reference will next be made to the rack bar structure and to the manner in which the various parts are adjusted into and out of functioning positions.

60 The rack bars are divided into entities, and as many entities as desired may be employed in accordance with the drying capacity desired. In the drawings, I have shown eight entities, each having two drying bars, but it will be understood 65 that additional drying bars for each entity may be employed if desired and the manner in which they may be incorporated will be clear from the present disclosure.

70 As all the rack bar entities are identical in form and function, only one need be described in detail, and they will be generally indicated at A.

75 Referring now more particularly to Fig. 1, an upper rack bar is shown at 31 and a lower bar at 32. The outer ends of these bars are pivoted

to the upper and lower ends, respectively, of a spacing bar 33. The pivotal connection of bars 31 and 32, to spacing bar 33, is preferably a permanent connection and these connections are indicated at 34 and 35. At their inner ends, bars 5 31 and 32, are provided with retaining pins 36 and 37, respectively, as shown in Figs. 5 and 7, which pins project from opposite sides of said bars and are adapted to occupy notches 16, as shown in Figs. 5 and 6. When the inner end of 10 one of said bars is disposed in a groove 15, with its retaining pins in the corresponding notches 16, such bar is held not only to a fixed radial position but also against movement in either direction lengthwise of said bar. However, this 15 is clearly an easily detachable connection and the bar is only supported at its inner end by its respective head 9 or 10, and this connection does not serve to support the bar from descending from a 20 horizontal position.

I employ a supporting bar 38, having its outer end pivoted at 35, and its inner end pivoted to the standard 1, at 39. In order to support all the drying entities from standard 1, I provide the latter with a supporting head 40, having a series 25 of jaws 41, equal in number to the number of drying entities with which the structure is equipped, and it will be understood that the pivotal connection to the supporting head will be preferably permanent and not detachable. It 30 will now be clear that the bars 31 and 32 are supported by bar 38, through spacing bar 33.

The operation will doubtless be clear from the foregoing description but it will be recapitulated 35 as follows:

With the parts folded as shown in Fig. 3, the entire structure is readily portable to any selected location, and when suitably located, the section 4 is extended as shown in Fig. 1, until the pad 7 is snugly engaged with the ceiling 8, while the 40 pad 3, is engaged with the floor 4, and consequently there can be no movement of the standard from such position, and the same has thus been stabilized.

The several rack bar entities will next be extended as shown at the left of Fig. 1, and finally those at the right will be similarly adjusted until all have taken the extended position shown in Fig. 2. The manner of attaching the bars 31 and 32, will have been made clear from the previous description. If the temperature of the room is such that heated air will aid in drying the clothes, then the heater will be plugged in, and if the fan is necessary, that may be connected.

55 The clothes are then hung on the bars 31 and 32, as shown in Fig. 1, and in practice, the bars will be much closer than herein-shown, and it will be clear that the clothes will be very effectively exposed to the heated air flowing out of 60 the openings 27 of the heater, and consequently, the drying action will be greatly hastened. This is due in great measure to the fact that the heater is located near the floor so that the heated air will take its natural ascent and because of 65 the close relation of the clothes, the latter will serve in a very efficient manner to deflect and spread the ascending heated air into engagement with all the clothes. A further advantage is that the clothes are radially disposed from the 70 standard and the heater, in addition to being located near the floor, is also centrally disposed with respect to the pendent clothes.

75 My improved drier not only has the capacity to handle large area pieces such as sheets, but

this feature is embodied in such a manner as to cause the sheets while being dried, to also function to confine the heated air.

Thus, as shown in Figs. 1, 2 and 4, the sheets are shown having their margins overlapping the outer ends of the upper bars 31, with the remainder hanging downwardly and in peripheral relation to the drier. The stringers 20, with the clips 21, serve to hold the upper margins of the sheets in the position shown, and if the sheets are disposed in the circumferential overlapping relation as shown in Fig. 4, then the ascending hot air will be confined in a most effective manner to the area inside of the surrounding sheets.

15 Of course, it will be understood that the inside areas of the sheets will also be exposed to the heated air and hence the sheets will be quickly dried.

As a means of holding the rack bar entities in a folded position, I have shown the head 10 provided with eyes 42, and short stringers or chains 43, extend about the folded bars and hold the latter against head 10.

It is believed that the utility and advantages of the invention will be fully understood from the foregoing description and while I have herein

shown and described one specific form of the invention, I do not wish to be limited thereto except for such limitations as the claim may import.

I claim:—

5 In a compactly foldable clothes drying rack structure, a normally unstable rack supporting standard having means for engaging the floor and ceiling to render said standard stable, rack bar heads mounted on said standard, a series of 10 clothes drying rack entities radiating from said standard and each entity comprising upper and lower substantially horizontal rack bars having their radially inner ends detachably supported on their respective heads, a spacing bar pivoted 15 to the other ends of said rack bars, a supporting bar pivoted to said standard and to the lowermost rack bar to coact with said heads in sustaining said rack bars in a radially extended position, said rack bars being detachable from their heads 20 and being adapted to be folded relatively to each other and said spacing and supporting bars against said heads, and means on one of said heads for holding said folded bars thereagainst.
